UNITED STATES PATENT OFFICE

128,971

DESIGN FOR A DISPLAY PAD FOR AN ARTICLE OF JEWELRY

Charles L. Thatcher, South Attleboro, Mass., assignor to Marathon Company, a corporation of Massachusetts

Application November 26, 1940, Serial No. 96,819

Term of patent 14 years

To all whom it may concern:

Be it known that I, Charles L. Thatcher, a citizen of the United States of America, residing at South Attleboro, county of Bristol, State of Massachusetts, have invented a new, original, and ornamental Design for a Display Pad for an Article of Jewelry, of which the following is a specification, reference being had to the accompanying drawing, forming a part thereof.

Fig. 1 is a top plan view of a display pad for an article of jewelry, showing my design, the chain and locket shown in dotted lines being merely illustrative of the manner of display thereof.

Fig. 2 is a side elevational view looking on substantially line 2—2 of Fig. 1 thereof.

The dominant feature of my design resides in the portions shown in full lines.

I claim:

The ornamental design for a display pad for an article of jewelry, substantially as shown and described.

CHARLES L. THATCHER.
